UNITED STATES PATENT OFFICE

LOUIS WERKSTELL AND ALDO COLOGNORI, OF BROOKLYN, NEW YORK

DESIGN FOR A WATCH

Application filed April 18, 1929. Serial No. 30,933. Term of patent 14 years.

To all whom it may concern:

Be it known that LOUIS WERKSTELL, a citizen of the United States, and ALDO COLOGNORI, a subject of Italy, both residents of the borough of Brooklyn, county of Kings, city and State of New York, have invented a new, original, and ornamental Design for Watches, of which the following is a specification, reference being had to the accompanying drawing, forming part thereof.

Fig. 1 is a plan view of a watch embodying my new design; and

Fig. 2 is a vertical elevation thereof.

I claim:—

The ornamental design for a watch as shown.

Dated New York city, April 11th 1929.

LOUIS WERKSTELL.
ALDO COLOGNORI.
